UNITED STATES PATENT OFFICE.

WILLIAM L. DEMING, OF SALEM, OHIO, ASSIGNOR TO THE DEMING COMPANY, OF
SALEM, OHIO, A CORPORATION OF OHIO.

LAWN SPRINKLER.

Application filed November 13, 1926. Serial No. 148,180.

This invention relates to lawn sprinklers and has for one of its objects the provision of a sprinkler, which may be easily moved from one location to another without danger 5 of tipping, and without requiring the water to be shut off.

A further object of my invention is the provision of a sprinkler of comparatively low height, which is so arranged that the 10 weight of the hose will not deflect the nozzle out of the normal position during or subsequent to the shifting movement. In this connection my invention is directed towards the construction of a sprinkler which may be 15 cheaply manufactured and which is durable in use.

In the drawings Fig. 1 is a plan view of a sprinkler embodying my invention; Fig. 2 is a vertical section through the longitudinal 20 center of the sprinkler; and Fig. 3 is a section through the sprinkler taken on a plane indicated by the line 3—3 in Fig. 2.

The invention as illustrated comprises a body portion having a pair of spaced 25 runners 10 which are connected along part of the upper edge by a web 11. The runners have substantially uniform depth for the length of the web, but have an increased depth on one end beyond the web. Moreover, the runners are flared outwardly adjacent such end portions, as shown particularly in Figs. 1 and 3. A nozzle 15 may be 30 swivelly mounted on the web adjacent the mid-portion of the rearward edge 12 and has provision for receiving a hose coupling indicated at 16. The swivel connection may embody a member 17 which is threaded onto the web, and which has a protruding portion 18 extending above the web and having an 35 annular groove 19 therein. A block 20 surrounds the protruding portion and in turn is mounted between downwardly projecting arms 21 which preferably form part of the body of the nozzle. A pin 25 extends 40 through the arms and the block, and also tangentially through the groove 19 for permitting the nozzle to be swiveled about the body, and at the same time for holding the cooperating parts together. In this way the 45 body may be positioned on uneven ground without causing the stream to be deflected from a vertical position. The dotted lines 10^a and 10^b in Fig. 2 illustrate two possible 50 positions of the body with reference to the nozzle.

The flared runners being higher than the distance of the web above the ground, provide adequate stops for the hose, while the sprinkler is being moved from one location to another, and by limiting the turning radius to prevent tipping of the device. The extreme positions of the hose are illustrated by the broken lines 27 and 28 in Fig. 1 while the normal position is shown by the full lines 29.

To facilitate turning of the sprinkler I employ a bail 30 which may be suitably fastened to the runners, and may utilize a ring 31 which slides around the bail and is arranged to be attached to a cord or chain 70 32. The bent portion of the bail near each end extends beyond the runners, as at 33, and facilitates turning of the sprinkler.

A swivel connection between the nozzle and body is illustrated as being on part of 75 the web which is depressed with relation to the main portion of the web. This permits the swivel connection to be comparatively low, wherefore the stream may not be deflected from a vertical direction by the weight of the hose. Thus, I obtain a sprinkler which embodies principally a one-piece casting which may be cheaply manufactured and yet provides a satisfactory nozzle support, which permits shifting of the nozzle in 80 a convenient manner.

I claim:

1. A lawn sprinkler having a pair of flared runners and a connecting web terminating short of the end of the runners, a nozzle pivotally mounted on the web adjacent the mid-portion and along one edge thereof, said nozzle having a hose connection associated therewith leading away from the web, each of the runners being flared upwardly on 90 opposite sides of the nozzle and adapted to engage the hose to limit the degrees of turning movement of the body with reference to the nozzle, and a bail associated with the body on the end opposite the flared part of the runners.

2. A lawn sprinkler comprising a body portion having a pair of runners and a connecting web, the runners being of a substantially uniform depth throughout the length of the web and being flared upwardly and outwardly beyond the web, a member attached to the web protruding beyond the top surface thereof and having an annular groove associated therewith, a nozzle sur- 105 110

- rounding the member, a connecting pin extending through the nozzle and said groove for providing a pivotal connection between the nozzle and the body, a hose connected to the nozzle, said flared portion of the runners being adapted to engage the hose to limit the turning movement of the sled with reference to the nozzle, and a bail associated with the runners.
- 10 3. A lawn sprinkler comprising a body portion having runners and a connecting member, a nozzle and hose connection swivelly connected to said connecting member, the runners being flared outwardly and upwardly to the rear of said connecting member

and in the path of lateral movement of the hose attached to said connection to provide a stop for limiting the swinging movement of the hose with reference to the body.

4. A lawn sprinkler comprising a body portion having a pair of runners and a connecting web, a nozzle and hose connection swivelly mounted on the web, and a bail associated with the body portion, said bail having the end portions bent into the form of loops which extend laterally beyond the sides of the runners.

In testimony whereof, I hereunto affix my signature.

WILLIAM L. DEMING.
